UNITED STATES PATENT OFFICE.

ANTONI IGNATOWSKI, OF CHICAGO, ILLINOIS.

BABBITTING-MACHINE.

1,208,788.

Specification of Letters Patent. Patented Dec. 19, 1916.

Application filed August 28, 1916. Serial No. 117,249.

To all whom it may concern:

Be it known that I, ANTONI IGNATOWSKI, a subject of the Czar of Russia, and a resident of Chicago, county of Cook, and State 5 of Illinois, have invented certain new and useful Improvements in Babbittting-Machines, of which the following is a specification.

The main objects of this invention are to 10 provide an improved machine adapted to hold railway journal box brasses when being lined with Babbitt metal; to provide in such a machine improved means for positioning and holding the journal box brasses during 15 the relining operation; to provide such a machine in which there are a plurality of adjustments so that brasses of varying sizes may be clamped therein; to provide a babbittting machine in which the mandrel may 20 be shifted so as to utilize a maximum number of sections of the surface thereof; and to provide improved means in such a machine for guiding the molten metal into the space between the brass and mandrel.

25 An illustrative embodiment of this invention is shown in the accompanying drawings in which—

Figure 1 is a top plan of a machine embodying four units. Fig. 2 is a transverse 30 sectional elevation taken on the line A—A, Fig. 1. Fig. 3 is a section taken on the line B—B of Fig. 2. Fig. 4 is a front elevation of the left hand end of the machine shown in Fig. 1. Fig. 5 is an enlarged sectional 35 detail taken on the line C—C of Fig. 4. Fig. 6 is a sectional detail taken on the line D—D of Fig. 2. Fig. 7 is a front elevation of the supporting stand with the rectangular framework in position thereon; the mechanism of 40 the framework being removed. Fig. 8 is a section taken on the line E—E of Fig. 7. Fig. 9 is a section taken on the line F—F of Fig. 7.

The machine herein to be described is 45 shown provided with four units, each one being a duplicate of the other, but it is to be understood that the machine may be built with any number of units and is not limited to the number herein shown.

50 In the construction shown in the drawings the rectangular supporting framework comprises side frame members 1 and 2 and end pieces or members 3 and 4 secured together at their adjacent ends by any suitable 55 means. The side frame members 1 and 2 are somewhat thickened at their middle por-

tions so as to add strength and rigidity to the structure. Cross bars 5, 6, 7 and 8 are mounted on the side frame members and are adapted to provide supports for mandrels 60 9, 10, 11 and 12 which are secured thereon by bolts and nuts 13 and 14 respectively. The mandrels are mounted vertically on the cross bars and are rotatably adjustable 65 thereon.

Each of the mandrels is provided with a pair of positioning strips 15 which are vertically disposed along the sides of the mandrel and parallel to the axis thereof. Sockets 16 are provided on the outer sides of the 70 strips substantially medially of the ends thereof. Adjustable clamps are provided for holding the strips tightly against the sides of the mandrel comprising a pair of jaws 17 and 18 pivoted together at 19. The 75 free ends of the jaws have inwardly facing hooks 20 formed thereon which are adapted to fit in the sockets 16 of the positioning strips. The jaws 17 and 18 are provided near the base thereof with lugs 21 and 22 respectively to which are pivoted a pair of bell crank levers 23 and 24 respectively. The bell crank levers 23 and 24 each have a long arm 25 and 26 respectively which form 80 handles and short arms 27 and 28 respectively which are provided with set screws 29 and 30 respectively and which bear against the jaws 17 and 18 and press these jaws toward each other when the handles 25 and 26 are spread apart.

The outer ends of the handles 25 and 26 are embraced between a pair of parallel members 31 and 32 which are held in spaced relation to each other by blocks 33 interposed therebetween. The members 31 and 32 85 are supported above the rear side member 2 by vertically disposed braces 34 which have their upper and lower ends bolted to the members and side frame respectively.

The units may be mounted in pairs as 100 shown in Fig. 1 so that the adjacent handles may be yieldingly pulled toward each other by connecting them with a tension spring 35 and chain 36, the outer handles of each pair being held by the blocks 33 which are 105 interposed between the members 31 and 32.

Each set of adjustable clamps is provided with means for preventing lateral shifting in a rearward direction comprising a bell crank lever 37 pivoted on the cross bar and 110 mounted so as to rock on a vertical plane. The arm 38 of the bell crank lever extends

upward through a clip 39 which is secured to the jaws 17 and 18 at their point of pivotal connection 19, and the arm 40 extends rearwardly underneath the members 31 and 32 and is provided with a tension spring 41, the upper end of said spring being provided with a threaded bolt 42 which passes through a clip 43 secured on the upper surface of the member 32. Tension on the spring 41 is varied by a nut 44 threaded on the bolt 42.

Means are provided for holding the railway journal bearing brass 45 against the positioning strips 15 and 16 and in spaced relation to the mandrels and comprise a standard 46 adjustably mounted on the cross bar and having an arm 47 pivoted thereon at 48 and a lever 49 pivoted to the upper end thereof at 50. The base of the standard 46 is adjustable toward and away from the mandrel by means of set screw 51. The arm 47 is adapted to bear against the journal-bearing brass 45 at its lower end and its upper end is provided with an adjustable set screw 52 which also bears against the brass 45. The inner end of lever 49 is adapted to wedgingly engage the arm 47 and the outer end is in the form of a handle for operating the same.

Means are provided for positioning the bases of the journal brasses when they are placed upon the mandrels and comprise positioning fingers 53 mounted on a rod 54 journaled in depending clips 55 and 56 mounted on the end pieces 3 and 4 respectively. The rod 54 is rotatable and axially shiftable and one end thereof is pivoted to a handle 57 which extends transversely across the end of the framework. The rear end 58 of the handle is adapted to slide in a vertically disposed slot 59 of a depending bracket 60 mounted on the end piece 4 and the forward end 61 of the handle is normally held in a horizontally disposed bracket 62 which is secured to the side member 1. A pivoted latch 63 is adapted to normally hold the handle in the position shown in Figs. 1 and 4.

Each of the mandrels is provided with a block 64 mounted on the top thereof which supports a horizontally disposed pin 65 which is threaded at its opposite ends to receive knurled nuts 66 and 67. The nuts 66 and 67 each carry the upper ends of a pair of side plates 68 and 69 respectively which have a transversely disposed shelf 70 mounted therebetween. The shelf 70 is secured to the side plates by means of bolts 71 and 72 which pass through upstanding lugs 73 and 74 on the shelf 70, said bolts passing out through the side plates and each having compression springs 75 and 76 mounted thereon between the side plates and nuts 77 and 78 on the outer ends of the bolts.

The side plates 68 and 69 and the transversely disposed shelf 70 form a gate which

is adapted to be swung down as shown in full lines in Fig. 2 so that the side plates yieldingly embrace the opposite sides of the journal-bearing brass and the shelf 70 rests upon the top thereof as shown in Fig. 5. 70 The shelf 70 slopes inwardly at 79 so as to guide the Babbitt metal into the space between the journal-bearing brass and the face of the mandrel.

A drip apron 80 is attached to and disposed underneath the front side of the frame work so that any molten metal which may be spilled during the babbitting operation is caught by the apron and guided back underneath the machine and is discharged into a drip box 81. 75

The rectangular frame work is provided at its corners with short tapered legs 82 which are adapted to fit into the tops of a suitable tubular supporting stand 83 as 85 shown in Fig. 7.

In the operation of the machine the railway journal-bearing brass is placed against the positioning strips which hold it in spaced relation to the mandrel and the arm 47 is 90 clamped thereagainst by means of the lever 49, the correct position of the bottom of the journal-bearing brass being determined by the positioning finger 53. The position of the strips 15 may be varied by means of the 95 adjustable clamping mechanism so that bearing brasses of varying sizes may be lined on the same machine. Rearward movement of the strips when the brass is clamped thereagainst is prevented by the upstanding arm 100 38 of the bell crank lever 37. The gate is then swung to the position shown in full lines in Fig. 2 so that the side plates embrace the opposite sides of the bearing brass and the transverse shelf is disposed immediately above the upper end of the brass. The Babbitt metal may then be poured onto the shelf 70 and is guided down into the space between the brass and the face of the mandrel, the side strips preventing any overflow of the metal particularly in cases where the edges of the journal-bearing brass have been broken away during the casting or use thereof. 110

With this arrangement the brass can be lined the entire length thereof. The 115 gate is then swung back to the position shown by dotted lines in Fig. 2, the latch 63 is raised up and the handle 57 is shifted to the left (Fig. 1) and then raised upwardly thereby sliding the rear end 58 down the 120 slot 59 and rocking the rod 54 so as to carry the positioning fingers out of the workman's way. The journal-bearing brass is then unclamped and removed.

The mandrels are rotatably adjustable so 125 that when one face thereof becomes roughened by use it may be turned to bring a new face into position. It will thus be seen that practically four different sections of the mandrel surface may be utilized. 130

All of the clamping mechanisms, positioning fingers and gates are readily adjustable so that journal-bearing brasses of varying sizes may be lined on this machine.

5 The dripping apron 80 catches any overflow of molten metal and keeps it from falling upon and burning the workman who is operating the machine.

Although but one specific embodiment of 10 this invention has been herein shown and described, it will be understood that numerous details of the construction shown may be altered or omitted without departing from the spirit of this invention as defined 15 by the following claims.

I claim:

1. A machine of the class described, comprising a framework, a mandrel mounted on said framework, said mandrel being rotatably adjustable on said framework, means for holding a journal-bearing brass in spaced relation to said mandrel so that molten metal may be poured into such space for lining said brass, said means comprising 20 a pivoted arm adapted to bear against said bearing brass at the upper and lower ends thereof, and a pivotally mounted lever, one end of said lever being shaped to form a handle and the other end thereof being 25 adapted to wedgingly engage said arm.

2. A machine of the class described, comprising a framework, a mandrel mounted on said framework, said mandrel being rotatably adjustable on said framework, 30 means for holding a journal-bearing brass in spaced relation to said mandrel so that molten metal may be poured into such space for lining said brass, and means for guiding the molten metal into said space, comprising 35 a pair of side plates and a transversely disposed shelf mounted between said plates.

3. A machine of the class described, comprising a framework, a mandrel mounted on said framework, said mandrel being rotatably adjustable on said framework, means for holding a journal-bearing brass in spaced relation to said mandrel so that molten metal may be poured into such space for lining said brass, and means for guiding 45 the molten metal into said space, comprising a pair of side plates and a transversely disposed shelf mounted between said plates, said side plates being yieldingly adjustable laterally with respect to said shelf.

55 4. A machine of the class described, comprising a framework, a mandrel mounted on said framework, means for clamping the journal-bearing brass against said mandrel, and means for positioning the base of said 60 journal-bearing brass with respect to said mandrel, comprising a rod, a positioning finger mounted on said rod, and a handle for moving said rod so as to carry said finger away from said journal-bearing brass.

65 5. A machine of the class described, com-

prising a framework, a mandrel mounted on said framework, means for clamping the journal-bearing brass against said mandrel, and means for positioning the base of said journal-bearing brass with respect to said 70 mandrel, comprising a rod, said rod being movable axially and rotatably, a positioning finger mounted on said rod, and a handle for moving said rod so as to carry said finger away from said journal-bearing brass. 75

6. A machine of the class described, comprising a framework, a mandrel mounted vertically on said framework, a pair of positioning strips vertically disposed along the sides of said mandrel, adjustable clamps for holding said strips in predetermined positions, means for holding a journal-bearing brass against said positioning strips, said clamps comprising a pair of pivotally connected jaws having their free ends bearing 80 against said strips, a handle pivoted to each of said jaws, said jaws and handles being constructed and arranged so that the spreading apart of said handles tends to close said jaws. 85

7. A machine of the class described, comprising a framework, a mandrel mounted vertically on said framework, a pair of positioning strips vertically disposed along the sides of said mandrel, adjustable clamps for holding said strips in predetermined positions, means for holding a journal-bearing brass against said positioning strips, said clamps comprising a pair of pivotally connected jaws having their free ends bearing 90 against said strips, a bell crank lever pivoted to each of said jaws, each of said levers having a long arm adapted to serve as a handle and a relatively short arm, and a set screw in each of said short arms in position 95 to bear against their respective jaws, said jaws and bell crank levers being constructed and arranged so that the spreading apart of said long arms tends to press said set screws against said jaws and close them. 100

8. A machine of the class described, comprising a framework, a mandrel mounted on said framework, said mandrel being rotatably adjustable on said framework, means for holding a journal-bearing brass in 115 spaced relation to said mandrel so that molten metal may be poured into such space for lining said brass, a block adjustably mounted on said mandrel, a horizontally disposed pin supported on said block, a pair of side plates carried on said pin, a transversely disposed shelf mounted between said side plates, bolts on said shelf which pass through said side plates, nuts on the outer end of said bolts, and compression springs mounted on said bolts between said nuts and side plates, so that said side plates are yieldingly adjustable laterally with respect to said shelf. 120

9. A babbitting machine, comprising a 130

framework, a mandrel mounted on said framework, means for holding a journal-bearing brass in spaced relation to said mandrel so that molten metal may be poured 5 into such space for lining said brass, and a drip apron disposed underneath the front side of said framework and sloping toward the rear thereof for guiding any overflow of molten metal away from a workman at the 10 front.

10. A machine of the class described, comprising a framework, a mandrel mounted on said framework, said mandrel being rotatably adjustable on said framework, means 15 for holding a journal-bearing brass in spaced relation to said mandrel so that molten metal may be poured into such space for lining said brass, said means comprising a standard mounted on said framework and adjustable toward and away from said mandrel, an arm pivoted at its lower end to said standard and adapted to bear against said bearing brass, a set screw threaded in the upper end of said arm and adapted to bear 20 against said bearing brass and a lever pivotally mounted on said standard, one end of said lever being shaped to form a handle and the other end thereof being adapted to wedgingly engage said arm.

30. 11. A machine of the class described, comprising a framework, a mandrel mounted vertically on said framework, a pair of positioning strips vertically disposed along the sides of said mandrel, adjustable clamps 35 for holding said strips in predetermined positions, means for preventing lateral shifting rearwardly of said clamps, and means for holding a journal-bearing brass against said positioning strips.

40. 12. A machine of the class described, comprising a framework, a mandrel mounted vertically on said framework, a pair of positioning strips vertically disposed along the sides of said mandrel, adjustable clamps for 45 holding said strips in predetermined positions, a bell crank lever mounted on said framework so as to rock in a vertical plane, one arm of said bell crank lever bearing against said clamps, means attached to the 50 other arm of said bell crank lever for urg-

ing said first mentioned arm against said clamps so as to prevent lateral shifting rearwardly of said clamps, and means for holding a journal-bearing brass against said positioning strips.

13. A machine of the class described, comprising a framework, a mandrel adjustable rotatably on a vertical axis on said framework, a pair of positioning strips vertically disposed along the sides of said mandrel, adjustable clamps for holding said strips in predetermined position, said clamps comprising a pair of pivotally connected jaws having their free ends bearing against said strips, a bell crank lever pivoted to each of said jaws, each of said levers having a long arm adapted to serve as a handle and a relatively short arm, a set screw in each of said short arms in position to bear against their respective jaws, 60 said jaws and bell crank levers being constructed and arranged so that the spreading apart of said long arms tends to press said set screws against said jaws and close them, means for clamping a journal-bearing brass 65 against said positioning strips and comprising a standard mounted on said framework and adjustable toward and away from said mandrel, an arm pivoted to said standard and adapted to bear against said bearing 70 brass, a lever pivotally mounted on said standard, one end of said lever being shaped to form a handle and the other end thereof being adapted to wedgingly engage said arm, means for guiding the molten metal 75 into the space between said bearing brass and mandrel, comprising a pair of side plates and a transversely disposed shelf mounted between said plates, said side plates being yieldingly adjustable laterally with 80 respect to said shelf, and means for positioning the base of said journal-bearing brass with respect to said mandrel, comprising a rod, a positioning finger mounted on said rod and a handle for moving said rod so 85 as to carry said finger away from said journal-bearing brass.

Signed at Chicago this 25th day of Aug. 1916.

ANTONI IGNATOWSKI.
